UNITED STATES PATENT OFFICE

2,535,200

TRAFFIC SIGNAL

Walter F. Freeman, Springfield, Mass.

Application October 4, 1948, Serial No. 52,671

2 Claims. (Cl. 177—337)

1

My invention relates to improvements in signal apparatus and is directed more particularly to the provision of a traffic signal device and to an improvement in the means for emitting signals for controlling traffic.

It is the principal object of my invention to provide a novel and improved signal construction of the type which is adapted and arranged for use at street intersections and the like.

With the above primary object in view, it is another object of my invention to provide a construction of the above described character which is relatively simple and compact in accordance with the demands and desires of purchasers as well as of the manufacturers thereof and which is not only attractive in its appearance and practical in its value but also reliable in its operation and thoroughly efficient in its use.

According to certain novel features of my invention, one or more signal members are provided which have a plurality of colored transparent members and these signal members are rotatable for shifting movements relative to windows in the casing of the apparatus.

According to other novel features of my invention, means is provided for rotating the signal members and for locking and releasing the same.

It is a still further object to provide a device which is constructed of relatively simple parts which are adapted to be readily assembled and which when once assembled are positively and securely retained in operative relationship and which cannot be readily separated from each other, either accidentally or otherwise.

Other prime objects of my invention include: first, the provision of a simplified construction and arrangement of a traffic signal device which is strong, durable and compact in its structure and is distinctive in its appearance; second, the securing of a higher degree of accuracy in the manner of work performed therewith than has heretofore been possible with prior devices known in the art; third, the attainment of a higher degree of speed of construction and assembly of the device due to its simplification in design and its unique composition of parts; fourth, the attainment of a flexibility or a capability of adjustment by which a large variety of work can be produced by means of the same device; fifth, the achievement of a greater ease in adjustment and repairs; sixth, the provision of an improved traffic signal device which may be made more economically and with fewer operations in the manufacture of its parts, as well as in the as-

2

sembly of the same, than prior devices known in the art; and seventh, the provision of a construction which may be readily installed.

These objects I accomplish by means of such structure and relative arrangement of parts thereof, as will fully appear by a perusal of the description below and by various specific features which will be hereinafter set forth.

To the above cited and other ends and with the foregoing and various other novel features and advantages and other objects of my invention as will become more readily apparent as the description proceeds, my invention consists in certain novel features of construction and the combination and arrangement of parts as will be hereinafter more particularly pointed out in the claims hereunto annexed and more fully described and referred to in connection with the accompanying drawings wherein:

20 Fig. 1 is a plan view of the signal apparatus embodying the novel features of my invention.

Fig. 2 is a combined side elevational and sectional view of the apparatus shown in Fig. 1.

Fig. 3 is a sectional view on the line 3—3 of Fig. 2.

Fig. 4 is a wiring diagram of the device of my invention, and

Fig. 5 is a perspective view of the contact arm of the apparatus.

Fig. 6 is a sectional elevational view on the line 6—6 of Fig. 2.

In the above mentioned drawings annexed hereto and forming a part of this specification, I have shown but one embodiment of my invention which is deemed preferable, but it is to be understood that changes and modifications may be made within the scope of the appended claims without departing from the spirit of the invention.

Referring now to the different drawings more in detail, in which similar characters of reference indicate corresponding parts in all the figures and referring more particularly to the preferred form of my invention selected for illustrative purposes, I have shown a casing or housing 2 which has a bottom wall 4, an upper wall 6, and pairs of side walls 8 and 10. Corner walls 12 are connected to adjacent side walls. The side walls are provided with windows such as shown at 14 in Fig. 2.

It will be noted that the side walls of the pairs thereof diverge from the walls 12 which are disposed between the pairs of side walls.

A signal supporting shaft 16 is journaled at opposite ends in bearings such as 18 which are

secured to opposite corner walls 12 between the pairs of side walls 8 and 10.

A signal member is provided for each pair of side walls and one form thereof is represented by 20 in Fig. 2. This member 20 has a hub 22 which is fixed to the shaft 16 and has a wall in the shape of a cone substantially as shown in Fig. 2.

The cone is formed from a transparent material such as glass or plastic and it is divided into segments 24 which may be of different colors as indicated.

As shown in Figs. 2 and 3, a hub 26 is fixed to the shaft 16 and arms which carry transparent signal members 28 may radiate therefrom. These members 28 may be transparent and of different colors as is indicated and may be so arranged that the planes thereof are disposed in the form of a cone so as to obtain a result identical with the result obtained with the signal member 20 in Fig. 2.

The shaft 16 is rotated so as to position one of the colored segments 24 or one of the members 28 adjacent each of the windows 14.

The colors selected will be those usually employed in traffic signals such as red, yellow and green.

A drive shaft 30 is provided which is rotatable in one or more bearings such as 32. The shaft may be operated from a motor or the like which will be energized for operation through a time device of any well known form.

A shaft 34 is rotatable in a bearing 36 and has a worm gear 35 fixed thereto which is in mesh with a worm 36' fixed on shaft 30.

A disc 38 is fixed to shaft 34 and has projecting from the rear face thereof a plurality of pins 40. A gear 42 is fixed to the shaft 16 and the teeth of this gear are engaged by the pins 40 as the disc 38 rotates.

The parts are so arranged that, as the shaft 30 is rotated to rotate shaft 34 by means of geared members 35 and 36, a pair of pins 40 of disc 38 engages gear 42 to rotate shaft 16. The pairs of pins are spaced about the disc 38 and the parts are arranged so that the shaft 16 is rotated through an arc of 90 degrees when a pair of pins engages and drives gear 42. As one pair of pins disengages gear 42, the shaft 16 is at rest until the next pair of pins engages the gear.

The interval of time between rotative movements of the shaft 16 may be varied by varying the gearing or by varying the operation of the shaft 30.

A means is provided for locking the shaft 16 against rotation during rotation of the disc 38 from one actuating position to another. This means includes an armature 50 which has a dog 52 receivable in slots 54 of the hub 22.

The armature is slidable up and down on pins such as 56 depending from a bracket 58 which is secured to the wall 12. An electromagnet 60 is secured to the bracket 58 and when energized it attracts and moves the armature upward from a slot 54 of the hub 22 whereby the shaft 16 is free to rotate.

A bracket 60' is secured to the lower wall 4 and a block of insulation 62 is pivoted thereto as by a pivot 66, as shown in Fig. 3. An arm 68 is secured to the block 62 and it has a rear portion 70 and a forward contact portion 72. An electromagnet 74 is disposed beneath the forward end 72 of the arm 68 which when energized attracts the arm. A post 76 carries a contact 78 which is engageable by the arm 68.

When the electromagnet 74 is energized the 75

arm 68 is free to swing downwardly, the end 72 of the arm engages the contact 78 so as to complete a circuit. The arm is attracted to the magnet which holds the arm in a circuit closing position until the magnet is deenergized.

A cam 80 is fixed to the shaft 34 and it has peripheral arm actuating portions 82 which, as the cam is rotated, engage an off-set portion 71 of the rear end of the arm 68 to elevate and hold the arm in an upper circuit open position.

When in rotation, a portion 82 of cam 80 passes off from part 71 of arm 68 and falls into a recess 84 of the cam, whereupon the arm swings downwardly.

15 As shown in Fig. 4, the electromagnets 60 and 74 are connected by a connection 88. A source of energy which may be a battery 90 is connected by connection 92 to electromagnet 60 and to arm 68 by connection 94. The electromagnet 74 is connected by connection 96 to contact 78.

The cam 80 is so related to the pins 40 that, when a pair of pins approaches the gear 42 to actuate it, the arm 68 is released by a cam portion 82 so that the arm drops into contact with the contact 78. This movement closes the circuit so that electromagnets 60 and 74 are energized, the arm being held in a circuit closing position by the electromagnet 74 and the armature 50 and dog 52 being moved upwardly by the electromagnet 60. In this way, the dog is withdrawn from a slot 54 of the hub 22 whereby the shaft 16 is free for rotation.

When the shaft 16 has been rotated through ninety degrees, a portion 82 of the disc 38 engages and elevates the arm 68 breaking the circuit and de-energizing the electromagnets. As electromagnet 60 is de-energized, the armature 50 and the dog 52 are released so that the dog drops into a slot 54 of the hub 22 to lock the shaft 16 against rotation.

Thus the shaft 16 is intermittently released for rotation and is rotated for positioning portions of the signal member adjacent the windows each signal member having portions adjacent 45 windows of relatively diverging walls and when the signal members are positioned the shaft 16 is locked against rotation.

Any desired form of illumination may be employed but for illustrative purposes a light bulb is shown at 100.

It will be noted that opposite portions of the signal members are disposed in diverging relation relative to the axis of rotation of shaft 16 and of the signal members so that said portions are disposed adjacent the pairs of side walls and over the windows therein.

The relative positions of the colored segments 24 to each other is important. That is to say, the traffic signal is for use at a street intersection and must separately signal vehicle and pedestrian traffic coming from different directions simultaneously.

As shown, the colors are so arranged as to each other that when a first side shows green meaning "go" a second side shows red meaning "stop" and when the first side shows yellow meaning "caution," the second side still shows red.

The invention may be embodied in other specific forms without departing from the essential characteristics thereof. Hence, the present embodiments are therefore to be considered in all respects merely as being illustrative and not as being restrictive, the scope of the invention being indicated by the appended claims rather than by the foregoing description, and all modi-

fications and variations as fall within the meaning and purview and range of equivalency of the appended claims are therefore intended to be embraced therein.

What it is desired to claim and secure by Letters Patent of the United States is:

1. Signal apparatus comprising in combination, a housing having bottom and side walls extending vertically upwardly therefrom and an upper wall secured to upper ends of the side walls, said side walls arranged in opposite pairs thereof, the walls of each pair disposed in diverging relation and extending towards the walls of the other pair, each of said side walls provided with windows therethrough, a shaft extending between and having opposite ends journalled for rotation in said side walls, signal devices fixed to said shaft adjacent opposite ends thereof, each said signal device including a plurality of circumferentially arranged colored transparent members, the transparent members of each said signal device diverging inwardly towards the members of the other said signal device and on an angle substantially similar to the angle of divergence of the walls of the pairs thereof whereby the members may be disposed inwardly of the windows, operating means to rotate said shaft in a step-by-step manner to position different transparent members of said signal devices adjacent the windows, a light bulb depending from said upper wall and disposed between said signal devices, and means to lock said shaft against rotation.

2. Signal apparatus comprising in combination, a housing having bottom and side walls extending vertically upwardly therefrom and an upper wall secured to upper ends of the side walls, said side walls arranged in opposite pairs thereof, the walls of each pair disposed in diverging relation

and extending towards the walls of the other pair, each of said side walls provided with windows therethrough, a shaft extending between and having opposite ends journalled for rotation in said side walls, signal devices fixed to said shaft adjacent opposite ends thereof, each said signal device including a plurality of circumferentially arranged colored transparent members, the transparent members of each said signal device diverging inwardly towards the members of the other device and on an angle substantially similar to the angle of divergence of the walls of the pairs thereof whereby the members may be disposed inwardly of the windows, operating means to rotate said shaft in a step-by-step manner to position different transparent members of the signal devices adjacent the windows, a light bulb depending from said upper wall and disposed between said signal devices, means to lock said shaft against rotation, and means operating said locking means under the control of said first named operating means.
